US00D462128S

(12) **United States Design Patent** (10) Patent No.: **US D462,128 S**
Careri (45) Date of Patent: **** Aug. 27, 2002**

(54) **SURFACE ORNAMENTATION FOR A DOOR
WINDOW**

Primary Examiner—Doris Clark
(74) Attorney, Agent, or Firm—Banner & Witcoff, Ltd.

(75) Inventor: **John Careri**, Toronto (CA)

(57) **CLAIM**

(73) Assignee: **Sunmark Glass, Inc.**, New York (CA)

The ornamental design for a surface ornamentation for a door window, as shown and described.

(**) Term: **14 Years**

DESCRIPTION

(21) Appl. No.: **29/147,518**

FIG. 1 is an elevational view of a surface ornamentation for a door window showing my new design;

(22) Filed: **Aug. 31, 2001**

FIG. 2 is a elevational view of a second embodiment of a surface ornamentation for a door window showing my new design; and,

(51) LOC (7) Cl. **25-01**

FIG. 3 is an elevational view of a third embodiment of a surface ornamentation for a door window showing my new design.

(52) U.S. Cl. **D25/103**

The broken line showing of the remainder of the door is for illustrative purposes only and forms no part of the claimed design. The depicted contrast in shading represents a contrast in appearance via color, texture, and/or luminance.
